UNITED STATES PATENT OFFICE.

WALLACE M. DILLON, OF WASHINGTON, DISTRICT OF COLUMBIA.

STRAINER.

REISSUED

Application filed October 23, 1925. Serial No. 64,319.

This invention relates to improvements in strainers and more particularly to a type especially adapted for filtering gasoline or the like where it is desired to remove all particles of sediment and water.

One of the objects of the present invention is to provide a simple and practical strainer comprising relatively few parts which may be inexpensively manufactured and assembled.

A further object is to provide a portable strainer of the above general character which may be easily taken apart for cleaning and whereby the interior parts may be removed 15 permitting the outer portion to be used as a container or funnel.

A further object is to provide a strainer of the above general character which will be strong and durable and not require the frequent replacement of parts as with strainers 20 now in general use, for example, by actual test it has been proven that the time consumed in refueling an airplane with this improved filter has been reduced to one-third of the time required with the use of the 25 commonly used chamois skin filter. The use of chamois skin not only makes refueling a long and tedious task, requiring time and patience, but causes the increased hazard of fire by the constant danger of the generation 30 of static electricity. The chamois skin soon becomes hardened and thereby loses its effectiveness and necessitates constant renewal.

Other objects will be in part obvious and 35 in part hereinafter pointed out in connection with the accompanying sheet of drawings illustrating one of various embodiments of the invention and in the several views of which corresponding parts are indicated by 40 similar reference characters.

In these drawings,

Figure 1 is a vertical longitudinal section of the device embodying features of the present invention.

Figure 2 is a sectional view taken substantially on the line 2/2 of Figure 1.

Referring now to the drawings in detail and more particularly to Figure 1, the embodiments hereinafter described comprise 50 preferably a cylindrical outer container 1 having a concave bottom 2 provided with a removable drain plug 23 for the purpose of removing the accumulation of water and sediment when it is not desired to take the 55 device apart for complete cleaning.

It will be noted that when the interior portions are removed as well as the plug 23 the container 1 may be used as a funnel.

Located near the lower part of the outer container 1 and several inches above the bottom 2 is positioned an outlet pipe 4 secured to the sides of the container 1 preferably by means of flanged bearing members 5 and 6 which form a support for the inner filter member 3 hereinafter described. The pipe 65 4 projects inwardly through one side wall of the container and has secured by means of a coupling 4^a a flexible hose member 7 for the purpose of more conveniently directing the flow of gasoline or the fluid to be 70 filtered into its receptacle.

When the hose member 7 is not in use, it may be secured in the position shown by means of spring 8 engaging the lower end of nozzle 7^a.

The inner hopper member 3 is preferably of frusto-conical shape and terminates in a cylindrical wire filter screen member 11 secured to its lower portion. This screen member 11 is composed of two spaced apart 80 circular flanged plates 12 and 13 held in spaced relation by a plurality of tubes 14 through which the gasoline freely passes from the hopper 3 to the space between the inner walls of the container and the filter 85 screen 15. The tubes 14, it will be noted are preferably flanged and soldered in place to provide a strong and durable construction.

The filter screen 15 is preferably made of very fine mesh bronze screen of a size approximating 200 thereby to eliminate the 90 passage of water or sediment to the interior of the tank.

In the center of the lower circular plate 13 is an aperture surrounded by a circular flange wheel 16 provided with elongated slots 17 for permitting the free passage of gasoline from the interior of the screen 15 out through the central aperture in the plate 13. The fitting 18 associated with the 95 protruding sleeve 19 cooperates with this aperture for directing the flow of gasoline into the outlet pipe 4. The lower part 19 of this fitting is provided with a boss 20 for the support of a threaded rod 21 which passes through the upper plate 12 and is threaded at its upper end for the reception of a nut 22. This nut when screwed down 100 securely holds the internal parts of the filter 105 in operative relation and on removal the 110

filter may be bodily removed from the container 1 for the purpose of cleaning or using the receptacle 1 as a funnel or container.

It is believed that the operation of this device will be clear from the above.

It may be stated, however, that the unfiltered gasoline is poured into the hopper 3 and passes down through the tubes 14 thus allowing the water and sediment to collect 10 in the concave bottom 2. The gasoline then passes in through the screen 15 and is thus thoroughly filtered and cleaned before passing out through the slot 17 to the outlet pipe 4 and nozzle 7^a. At intervals the block 15 23 is removed for the purpose of removing water and sediment. When a thorough over-hauling is desired, the nut 22 is removed permitting all of the parts above the outlet pipe 4 to be removed.

20 It will thus be seen that the present invention provides a simple and practical filter, reliable and efficient in operation, inexpensive to manufacture, durable in construction and well adapted to accomplish, among 25 others, all of the objects and advantages herein set forth.

What I claim is:—

1. In a portable strainer of the character described, in combination, an outer container, 30 a hopper, a member attached to the hopper, the side wall thereof being a filter and well above the bottom of the container, means extending through the member longitudinally

of the container for conducting an entering fluid from the hopper to the bottom of the 35 container, means for conducting the fluid to the exterior of the container after it has passed through the filtering wall, and means connecting the conducting means with the filtering member.

2. In a portable strainer of the character described, in combination a container, a vertically disposed filter screen of drumlike construction having its central outlet communicating with the exterior of the container, and vertical conduits extending through the filter for conducting a fluid therethrough 45 prior to its being filtered by the vertical screen.

3. In combination, a cylindrical filter member having closed top and bottom and a filtering side wall, conduits extending through said member for conveying an entering fluid through the member prior to its being filtered, a container in which said filter member is centrally disposed, and an outlet from the interior of said strainer to the exterior of the container, said container being provided at its lower part with a normally closed opening for permitting the removal of sediment or water as and when desired.

Signed at Washington, District of Columbia, this 31st day of July, 1925.

WALLACE M. DILLON.
